INVENTOR
MARIE MILLER

BY *Fatherston Daugherty* ATTY.

UNITED STATES PATENT OFFICE.

MARIE MILLER, OF OTTAWA, ONTARIO, CANADA.

ELECTRIC HAIR-CURLER.

1,400,305.

Specification of Letters Patent. Patented Dec. 13, 1921.

Application filed March 22, 1920. Serial No. 367,790.

To all whom it may concern:

Be it known that I, MARIE MILLER, a subject of the King of Great Britain, a resident of the city of Ottawa, Province of Ontario, 5 Dominion of Canada, have invented certain new and useful Improvements in Electric Hair-Curlers, of which the following is a specification.

This invention relates to improvements in 10 electric hair curlers, and the objects of the invention are to permit of the desired number of curls being curled in a single operation, that is to say to permit of the hair being divided into strands and each strand 15 wound on a separate curler and then all the curlers heated electrically at one time, to uniformly distribute the heat among all the curlers, to permit of the curler being attached to any standard light socket. 20 Further objects still are to render the curlers easy to handle, to prevent the hair becoming detached from the curlers, during the curling operation, and generally to adapt the curlers to better perform the functions required of them. 25

With the above and other objects in view, the invention consists essentially of the improved construction particularly described and set forth in the following specification 30 and accompanying drawings forming part of the same.

In the drawings:

Figure 1 is an enlarged view of one of the curlers and showing the means attaching the same to a light socket. 35

Fig. 2 is a longitudinal section of the improved curler.

Fig. 3 is a longitudinal section through the caps at one end of the casing of the 40 curler, and the ring or cap on the other end of the casing.

Fig. 4 is a perspective view of the caps used on one end of the casing of the curler for holding the elastic in position.

Fig. 5 is a side elevation of a socket connection whereby the curlers are connected to main wires designed to be attached to a lamp socket. 45

Like characters of reference refer to like parts in the several figures. 50

Referring to the drawings; A represents one of the improved curlers comprising a casing 10 on one end of which a ring 11 is threaded, the opposite end of the casing 10 being closed as shown at 12. 55

In the casing 10 a heating coil or resist-

ance 13 is housed, and a plug 14 fits the open end of the casing 10, and through this plug 14 a pair of wires 15 and 16 extend to engage with the terminals 17 and 18 of the resistance 13. The wires 15 and 16 have their opposite ends connected to a socket 19. 60

It will be readily understood that this socket 19 is a multiple type that is to say a sufficient number of pairs of wires extend 65 therefrom to be connected to an equal number of curlers to be used.

Coacting with the socket 19 is a socket 20 from which the main wires 21 extend, and these main wires 21 are connected to a standard screw plug 22, which may be threaded 70 into an ordinary light socket commonly used in households.

The strand of hair to be curled is twisted around the outer periphery of the casing 10, 75 and to hold the hair in coiled position, I provide a pair of longitudinally extending elastic members 23, one end of each of which engages with the threaded ring 11 on diametrically opposite sides thereof and an outer ring or cap 24 is pressed over the inner ring 11, and frictionally embraces the ends of the elastic 23 between the outer cap 80 and the inner ring.

The other ends of the elastic members 23 85 are embraced between an inner and outer cap 25 and 26 and the inner cap embraces the closed end of the casing 10.

When the hair is coiled around the casing 10, the elastic members 23 will engage with 90 the hair, and when the cap 25 is engaged with the end of the casing 10 the members 23 will hold the hair in position.

When the curling operation is completed the caps 25 and 26 are removed as a unit 95 from the end of the casing 10 so liberating the elastic members 23 from engagement with the coil of hair, and the casing 10 may then be pulled longitudinally through the coil of hair which is left in a curled 100 condition.

In using this curler the hair is divided into a certain number of strands depending upon the number of curls desired, and each strand is then coiled around the casing 105 of the individual curler.

Each coil of hair is then engaged by the elastic members 23 of its curler and so prevent the hair uncoiling, and, when the desired number of curlers are in commission, the operator engages the plug 22 with 110 an ordinary standard screw light socket,

thus heating the resistances of each curler, and so curling the several strands of hair.

When the heating operation is completed, the plug 22 is removed from the socket and 5 each coil of hair is disengaged from its curler.

In this way the curling operation is completed in a single heating operation, and there is no possibility of singeing and otherwise 10 destroying the hair during this curling operation, and the desired temperature is always obtainable. Moreover the several parts can be constructed of material best suited for the purpose, so that the operator 15 will not get shocks or burn her fingers.

As many changes could be made in the above construction and many widely different embodiments of my invention within the scope of the claims, constructed 20 without departing from the spirit or scope thereof, it is intended that all matter contained in the accompanying specification and drawings shall be interpreted as illustrative and not in a limiting sense.

25 What I claim as my invention is:
1. A hair curler of the class described

comprising a cylindrical casing open at one end and closed at the other end, a resilient member, a pair of concentrically arranged caps between which a portion of 30 the resilient member is frictionally retained, the ends of the resilient member extending longitudinally of the casing but on opposite sides thereof, a cap for the open end of the casing designed to secure the free end 35 of the resilient member to the casing, and a heating element within the casing.

2. A hair curler of the character described comprising a cylindrical heating element, a cylindrical casing surrounding the 40 same, a retaining member adapting to support the hair on the casing comprising a pair of longitudinally extending elastic members, caps engaging the opposite ends of the elastic members and adapted to fit 45 around the ends of the casing.

In witness whereof I have hereunto set my hand in the presence of two witnesses.

MARIE MILLER.
